C. E. PETERSON

BUCKLE

Filed Apr. 29, 1922

INVENTOR
Carl E. Peterson.

BY
Wm H. Campfield,
ATTORNEY

UNITED STATES PATENT OFFICE.

CARL E. PETERSON, OF BRIDGEPORT, CONNECTICUT.

BUCKLE.

Application filed April 29, 1922. Serial No. 557,293.

To all whom it may concern:

Be it known that I, CARL E. PETERSON, a citizen of the United States, and a resident of Bridgeport, county of Fairfield, and 5 State of Connecticut, have invented certain new and useful Improvements in Buckles, of which the following is a specification.

This invention relates to an improved buckle which consists of a main buckle part 10 of any usual type adapted to be fastened to one end of a strap and to adjustably secure the other end of the strap, such as the ends of a belt and the like, and having a face plate, which face plate has no function 15 as to holding the strap, but which forms an ornamental and secure means for covering the front of the buckle to improve its appearance, and furthermore, to prevent parts of the clothing or parts of the hand 20 from being damaged by engagement with the tongue or other protruding parts of the main buckle.

The invention is illustrated in the accompanying drawing, in which Figure 1 is a front view of one form of my improved 25 buckle. Figure 2 is a similar view with the face plate swung to an open position. Figure 3 is a section on line 3-3 in Figure 1. Figure 4 is a front view of a modified form 30 of buckle with its face plate swung to open position. Figure 5 is a longitudinal section through Figure 4, taken on the line 5-5, Figure 4, and Figure 6 is a back view of an improved buckle, showing a still further 35 modification.

The main buckle part, which can be of any desired form, is shown in Figures 2 and 3 as being a buckle made of wire, the main portion 10 consisting of the side bars 11, a 40 center bar 12, a front bar 13 and a rear bar 14, the terms "front" and "rear" being simply used to differentiate the opposite ends of the buckle. On the center bar 12 is a tongue 15 which swings on the center bar 45 and is adapted to pass through the holes in a strap to hold it in position. While a buckle using a tongue is illustrated, it will be evident that other forms of buckle can be used for holding the strap.

50 The face plate 16 is adapted, when closed, to give the buckle the appearance of an ornamental, substantially oblong fastening and completely covers the buckle and is readily removable from at least a part of 55 the main buckle portion so as to permit the

adjustment of the strap and its disengagement from the tongue 15.

In Figures 1, 2 and 3 I show the face plate 16 hinged at one end by having the material of the face plate bent back to form 60 a sleeve 17 which embraces the back bar 14 so that the main buckle portion and the face plate are hinged together, and the front end is yieldingly held in closed position by the fingers 18 on the end of the lateral strip 19, these fingers projecting so that when the buckle is closed the fingers are snapped over the side bars 11 adjacent to the front bar 13, as will be clearly seen from Figure 70 3. The strip 19 can be held in position by soldering or other means, or by folding over the part 20 from the front end of the face plate, and crimping it down at its edge so that it holds the strip substantially rigid 75 against the back face of the face plate.

To permit the face plate to be tightly pressed against the buckle the end of the tongue 15 does not contact with the part 20 because the part 20 is provided with a cut away portion 21. When the face plate is 80 swung open, as shown in Figure 2, the belt can be adjusted because the main buckle portion 10 is free to be manipulated for the adjustment of the end 22 of the strap or belt, the other end of which can be secured, 85 as at 23, to the center bar of the buckle. When the parts are adjusted as desired, all that needs to be done is to swing the face plate to its closed position and it clicks or snaps into holding engagement with the 90 main buckle part by reason of the fingers 18 engaging the main buckle, the main buckle being thus entirely concealed, since the top part of the face plate is provided with rearwardly projecting flanges 24 at the top and 95 25 at the bottom. The fingers 18 are within the top and bottom flanges and are thus concealed and also prevent any distortion of the flanges when the parts are snapped together. This leaves the flanges smooth 100 and even.

In Figure 4 I show a modified form in which a substantially narrow buckle can be provided for, being not much wider than the strap to which it is secured, this buckle 105 being of the cast type, the main buckle part 26 having the front bar 27, the center bar 28 and the rear bar 29 secured to the side bars 30, the front bar having fingers 31 projecting from the front thereof, the face plate 110

16 being hinged by the sleeve 17 to the rear bar 29, the face plate on the front end having the strip 19 with its spring fingers 18, the spring fingers, however, being arranged 5 so as to engage the fingers 31 on the front bar 27 of the main buckle portion. The flanges 24 and 25 can thus be made slightly wider than the distance between the outside edges of the side bars 30.

10 In Figure 6 I show a still further modification which requires no cut out portion to compensate for the end of the tongue 15, this being accomplished by extending the front end of the face plate beyond the main buckle portion so that the end 32 of the 15 folded over part 20 is beyond the end of the main buckle portion, and therefore beyond the end of the tongue, the strip 33 being bent so that the spring fingers 34 on the 20 ends of it will extend back so as to engage the side edges of the side bars 11 of the main buckle.

I claim:

1. A buckle comprising a main buckle 25 with means therein for holding the ends of a strap, and a face plate hinged at one end to the buckle, said face plate having top and bottom flanges and spring ears secured to the face plate within the flanges to engage the other end of the buckle so as to hold the plate on the front of the buckle.
2. A buckle comprising a main buckle with means therein for holding the end of a strap, and a face plate having inwardly

extending flanges on its top and bottom edges and being bent into a sleeve at one end so that it will embrace one bar of the buckle, and having fingers secured to the face plate independent of and within the flanges, said fingers being adapted to yield and to embrace the front end of the buckle so that the face plate is yieldingly held in position.

3. A buckle comprising a main buckle with means therein for holding the end of a strap, a face plate having inwardly extending flanges on its top and bottom edges and being bent into a sleeve at one end so that it will embrace one bar of the buckle, and a strip of metal on the inner face of the face 50 plate and having its ends bent to form fingers adapted to yieldingly engage the front end of the buckle, the front end of the plate being bent over to hold said strip in position.

4. A buckle comprising a main buckle, a face plate hinged to one end of the buckle, and a lateral strip secured to the buckle, said strip having spring fingers on its ends and within the top and bottom edges of the 60 face plate, said fingers being disposed so as to engage the sides of the buckle to hold the face plate shut.

In testimony that I claim the foregoing, I have hereto set my hand, this 28th day 65 of April, 1922.

C. E. PETERSON.
